UNITED STATES PATENT OFFICE.

JULIUS A. SCHWEIG, OF ST. LOUIS, MISSOURI.

ELEVATOR DOOR.

Application filed May 3, 1928. Serial No. 274,691.

This invention relates to counterbalanced fireproof freight elevator doors of the pass-type wherein the top and bottom sections of each door are arranged for vertical sliding movement in different planes so that the upper section of the door on one floor slides past the lower section of the door on the floor above, while the lower section slides between the wall in which the door opening is formed and the upper section of the door on the floor below; and the invention relates more particularly to the means for closing the space between the wall and the upper section of a door in the closed position of adjacent doors to prevent passage of flames, smoke and water through said space in the event of fire.

The principal object of the present invention is to provide a simple and efficient fire stop for closing the space between the top of the upper door section and the wall in the closed position of said section which will not interfere with the upward movement of the upper section or the downward movement of the lower section of the door located on the floor above. Another object is to provide means, releasable by the relative sliding movement of the upper door section on one floor and the lower door section on the floor located thereabove, for locking the fire stop in operative position in the closed positions of said sections. Other objects are simplicity and cheapness of construction and compactness of design. The invention consists in means for automatically locking the fire stop in operative position when doors on adjacent floors are closed; it also consists in means, operated by the opening movement of either of said adjacent doors, for unlocking said fire stop; and it also consists in the parts and in the combinations and arrangements of parts hereinafter described and claimed.

In the accompanying drawings, which form part of this specification and wherein like symbols refer to like parts wherever they occur;

Fig. 1 is a vertical section through an elevator shaft, showing the door openings on adjacent floors equipped with counterbalanced pass-type doors provided with fire stops embodying my invention;

Fig. 2 is an enlarged fragmentary vertical cross-section showing the adjacent portions of the upper door section of one floor and

the lower door section of the floor located thereabove, said doors and said fire stop being shown in closed position;

Fig. 3 is a cross-section similar to Fig. 2 showing one of the sections of adjacent doors opened in overlapped relation and the fire stop unlocked and swung open;

Fig. 4 is an inside view of the corner portions of the two door sections shown in Fig. 2; and

Fig. 5 is a horizontal cross-section through one side of the door opening, the section being taken above the fire stop on the line 5—5 in Fig. 2.

Referring to the accompanying drawings, my invention is shown in connection with an elevator shaft A whose door openings B are equipped with counterbalanced fire proof freight elevator doors of the pass-type. This construction of door comprising upper and lower sections or panels C and D, respectively, located in the elevator shaft and arranged for vertically sliding movement in different planes, so that the upper section C of one door and the lower section D of the door located on the floor above are adapted to move into overlapped relation when either of said doors is opened. As shown in the drawing, the upper and lower sliding door sections C and D of each door are provided along each vertical edge with an angle bar 85 frame member 1 slidably arranged between angle bar guides 2, which extend substantially the entire height of the elevator shaft and are rigidly secured to each other and to the adjacent jamb members 3 of the door 90 openings. The upper and lower door sections are connected together and movably suspended from the frame work of the elevator shaft by the usual counterbalancing means (not shown) whereby the two sections 95 move simultaneously in opposite directions when the door is opened or closed. This pass-type counterbalanced fireproof elevator door construction is well known and is considered unnecessary to illustrate it in detail.

Mounted on the top angle 4 of each upper door section C for each door opening is a fire stop E which serves to normally close the space between said section and the adjacent wall of the elevator shaft. As shown in the 105 drawing, said fire stop comprises a shield or plate 5 of substantially angle-shaped cross-section which extends along the top of the

upper door section from side to side thereof and is arranged with one flange up and extending across the gap between said section and the wall of the elevator shaft and with 5 the other flange down and terminating adjacent to the upper edge of said door section. The angle-shaped fire stop or lintel is pivotally supported on top of the upper door section for vertical swinging movement thereon preferably by means of butt hinges 6 having one leaf secured to the underside of the top flange of the fire guard and having the other leaf secured to the inner face of the upstanding flange of an angle bar 7 whose other flange 10 rests on and is rigidly secured to the top angle of said upper door section. The pivotally supported fire stop is normally held with its top flange in a substantial horizontal position and extending across the space in the upper door section of the wall in the elevator by 15 means of a counterweight 8 in the form of a strip of metal secured to the inner face of the depending flange of said fire stop.

In the closed positions of elevator doors on 20 adjacent floors, the pivotal fire stop is locked in position to close the gap between the upper section and the wall by means of a gravity lock in the form of a latch arm 8^a mounted on each end of the fire stop. As shown in 25 the drawing, the latch arm 8^a at each end of the fire stop is pivotally mounted for vertical swinging movement between the vertical side flanges of a channel-shaped bracket 9 whose web portion is riveted or otherwise rigidly secured flatwise to the inner face of the depending flange of said fire stop. The upstanding flange of the angle 7 terminates short of each 30 end thereof so as to provide space for the latch arm 8^a and its supporting bracket 9. 35 At each end of the upstanding flange the angle is notched out to form an abutment flange 10 of reduced height which extends beneath the latch arm 8^a and cooperates with a depending hook portion 8^b that overhangs 40 the edge of said abutment flange and thus prevents downward swinging movement of top flange of said fire stop in the closed position thereof. The free end of the latch is made heavy enough to hold the same down in 45 the flange 10. If desired, the latch may be held down on the abutment flange 10 by pressure exerted by a spring 11 interposed between the opposing faces of said catch and the web of the supporting bracket therefor. 50 As shown in the drawings, one end of the spring 11 is mounted in a recess provided therefor in the latch arm and the other end thereof seats in a recess provided therefor in the web of the supporting bracket. 55 The latch is swung upwardly to disengage 60 the hooked end thereof from the flange 10 to permit downward swinging movement of the horizontal flange of the fire stop by means of a lifter lever 12 mounted for vertical swinging 65 movement in the channel-shaped bracket

which pivotally supports the latch arm. As shown in the drawing, the lifter lever is located at one side of the latch arm and has a depending arm 13 extending downwardly along side of said latch arm between two pins 70 14-14 which project horizontally from the adjacent side thereof. The other arm 15 of the lifter lever extends inwardly beneath the horizontal top flange of the fire stop and terminates in an upstanding end portion 15^a 75 which extends through an elongated slot 16 provided therefor in said top flange. A shoe 17 is secured to each end of the lower door section of a door immediately above the upwardly projecting free end portion 15^a of the 80 lifter lever 12 of the fire stop mounted on the upper section of the door on the floor located therebelow. As shown in the drawings, said shoe 17 preferably comprises a channel-shaped member having one flange secured to 85 the side rail of the lower door section by means of bolts 18 which pass through the vertical slots 19 provided therefor in said side rail whereby said shoe is vertically adjustable on said door.

By the arrangement described, when the doors on adjacent floors are closed, the fire stop carried by the upper door section is firmly locked to said door section with its upper horizontal flange extending across the space 95 between said section and the wall of the elevator shaft. When the door on one floor is opened the upper section will move upwardly and thus cause the upwardly extending inner end portion 15^a of the lifter lever 12 to 100 abut against the shoe 17 on the lower section of the door on the floor thereabove, thereby causing said lever to swing downwardly and force the depending arm thereof against one of the pins 14 on the side of the latch arm 8^a 105 and thereby cause said arm to swing upwardly and the hook portion 8^b thereof to become disengaged from the abutment flange 10 at the end of the upstanding flange of the angle 7 on top of the door section. Upon release 110 of the latch arm further upward sliding movement of said upper door section causes the top flange of the fire stop to engage the shoe 17 and thus cause the fire stop to swing on its hinge and permit the upper door section to slide past the lower door section located thereabove. It is noted that the latch arm has a curved surface 20 at its outer end which is disposed eccentric to the pivotal axis 115 of the fire stop, whereby said surface gradually approaches the top edge of the abutment flange 10 during the opening movement of the fire stop and finally contacts with said edge in the fully opened position of said fire stop to prevent further outward swinging 120 movement thereof. It is also noted that in the open position of the fire stop the latch arm bears against the top edge of the abutment flange 10 and against the inner face of the fire stop and is thus held against swinging 125 130

movement in such position of said stop. In the open position of the fire stop and latch arm, the lifter lever 12 is also held against swinging movement with its upwardly curved 5 free end portion 15^a flush with the upper surface of the top flange of the fire stop by means of the two pins 14 carried by said latch arm and located on opposite sides of the arm 13 of said lever, thereby preventing the door section 10 from engaging said lever in the open position of said fire stop. During the opening of the door the lower door section also moves downwardly and strikes the lifter lever on the fire stop carried by the upper section of 15 the door located on the floor therebelow, thereby unlocking said fire stop and permitting the same to swing downwardly and permit the lower door section to pass between the upper door section and the elevator wall. 20 The herein described fire stop has numerous advantages. It serves to close the space between the upper door section and the elevator wall; it is automatically locked in closed position when the doors are closed, and cannot 25 be swung open by back drafts or by the pressure of water; and it is automatically unlocked by the opening movement of said doors. It is of simple, economical construction and may be quickly and easily applied to 30 the doors without substantial alteration thereof.

What I claim is:

1. A pass-type fire door construction comprising two sections slideable in different vertical planes, a fire stop for automatically closing the space between the wall in which the door opening is formed and the section more remote from the wall when doors on adjacent floors are closed, means for automatically locking said fire stop in closed position when adjacent doors are closed, and means whereby the locking means for said fire stop is released by the opening movement of either of said adjacent doors. 40
2. A pass-type door construction comprising upper and lower sections, a fire stop for automatically closing the space between the wall in which the door opening is formed and the upper section when both doors are closed, means for automatically locking said fire stop in closed position when adjacent doors are closed, and means whereby the locking means for said fire stop is released by the opening movement of either of said adjacent doors. 50
3. A pass-type door construction comprising upper and lower sections, a fire stop pivotally supported on the upper section for closing the space between the wall in which the door opening is formed and the upper section 60 when both doors are closed, a latch pivotally supported on said fire stop for locking the same to said section in closed position when both doors are closed, and a lifter lever pivotally mounted on said fire stop and for disengaging said latch from said section, said lifter

lever having a portion located in position to be actuated by engagement with the lower section of the door located on the floor above.

4. A pass-type door construction comprising upper and lower sections, a fire stop pivotally mounted on the upper section for normally closing the space between the wall in which the door opening is formed and said upper section when adjacent doors are closed, a counterweight for normally maintaining 70 said fire stop in closed position, a gravity latch pivotally mounted on said fire stop and adapted to cooperate with said section to lock said fire stop in closed position, and a lifter lever pivotally mounted on said fire stop in 75 position to release said latch upon engagement with the lower section of the door located thereabove.

5. A pass-type door construction comprising upper and lower sections, a fire stop pivotally mounted on the upper section for normally closing the space between the wall in which the door opening is formed and the upper section, means for normally maintaining said fire stop in closed position, a latch arm 80 pivotally mounted on said fire stop and adapted to cooperate with the upper section to prevent opening movement of said fire stop, a lever pivotally mounted on said fire stop and having one arm cooperating with said latch 85 arm to move the latter into and out of latching position, the other arm of said lever being located in position and operated by engagement with the lower section of the door located thereabove. 90

6. A pass-type fire door construction comprising two sections arranged in different vertical planes, the top section being spaced far enough away from the wall in which the door opening is formed to permit the upper section of said door and the lower section of a similar door on the floor above to move into overlapped relation when either of said doors is opened, a fire stop carried by said upper section and movable into a position to close 100 the space between the upper section and the wall when both of said doors are closed, means for locking said fire stop in closed position when both doors are closed, and means for unlocking said fire stop to permit the upper section and the lower section of the door on the floor above to move into overlapped relation. 105

7. A pass-type fire door construction comprising upper and lower sections slideable in different vertical planes, a fire stop pivotally mounted on the upper section for normally closing the space between the wall in which the door opening is formed and said upper section, a gravity latch pivotally mounted 120 on said fire stop and adapted to cooperate with said upper section to lock said fire stop in closed position, a lifter lever pivotally mounted on said fire stop for releasing said latch, 125 and a shoe adjustably mounted on said lower 130

section in position to engage a similar lifter lever on the upper section of the door on the floor below.

8. A pass-type door construction comprising upper and lower sections, a fire stop pivotally mounted on the upper section for normally closing the space between the wall in which the door opening is formed and the upper section, means for normally maintaining said fire stop in closed position, a latch arm pivotally mounted on said fire stop and adapted to cooperate with the upper section to prevent opening movement of said fire

stop, a lever pivotally mounted on said fire stop and having one arm cooperating with 15 said latch arm to move the latter into and out of latching position, the other arm of said lever being located in position and operated by engagement with the lower section of the door located thereabove, and means for preventing engagement between said lever and said last mentioned door section in the open position of said fire stop.

Signed at St. Louis, Missouri, this 30th day of Apr., 1928.

JULIUS A. SCHWEIG.
